[57] **CLAIM**

The ornamental design for a pillow, as shown and described.

DESCRIPTION

FIG. 1 is a front elevational view of a pillow showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The pattern of squares and criss-crossing shown fragmentarily in FIGS. 1-4, and 6 is understood to extend throughout the face and ears of the pillow.
